BUTTON

Application filed May 11, 1928. Serial No. 276,845.

The invention relates to buttons and more particularly to decorative buttons of that type commonly referred to as cuff buttons which comprise cooperating sections including male and female members capable of being detachably connected with each other and separated at will.

The object of the invention is to supply the jeweler-manufacturers of such cuff buttons with assembled structural units wholly complete except for the ornamental or decorative faces which the jeweler-manufacturer selects and applies in completing the production of the cuff button.

Heretofore it was customary for the jeweler to make up his own structural units from a plurality of separate parts comprising a base, a stem, a head and the decorative element, for each button section. This practice required the jeweler to apply at least one riveting operation and two crimping operations for each button section. The manufacture of buttons on that basis involved not only special labor and expense in assembling, but these buttons were subject to the disadvantage that the base and the stem, even though the riveting operation was carefully carried out, were frequently capable of movement relatively to each other and even separated completely.

The new structure described in this specification avoids many of the objectionable features of existing constructions and provides button sections at least equal in strength to existing types and superior thereto in eliminating disadvantages thereof. The invention will be fully described hereinafter and the features of novelty will be pointed out in the claims.

In the accompanying drawings, which illustrate examples of the invention without defining its limits, Fig. 1 is an elevation, partly in section, showing the two button members in detachable connection with each other; Figs. 2 and 3 are sectional elevations of the two button sections; Figs. 4 and 5 are side elevations of the separate elements comprising said sections; and Fig. 6 is a sectional view taken on the line 6—6 of Fig. 2 and has parts at the edge of the button

shown as dotted for the purpose of illustrating the internal structure.

As shown in the drawing the button consists of two separable members F and M, F representing a female member and M a male member. The ornament-carrying plates 16, 11 and 11^a (see Figs. 2, 3, and 5) of these two members may be of any suitable configuration especially adapted to accommodate the ornament. The plates 16 and 11, although illustrated as round, may obviously be of any other appropriate shape, such as hexagonal, square, rectangular, etc. The periphery of these plates may be used as a shoulder for engaging a metal ring 25 which, as shown in Fig. 2, holds the ornament 24 in place, or the plates may be initially formed in a cup or dish shape as shown at 26 in Fig. 3, in which case the concave recess serves as a depository for the ornament which is then held in place by bending or crimping the edges 26 of the plate 11^a of Fig. 3 over the edges of the ornament.

The members F and M are constituted of material such as brass which possesses the necessary physical working characteristics and the strength required by my structural arrangement. Material of this character is first drawn or otherwise treated to develop integral units comprising in the female member F the hollow stem 12 and the plate 10 (Fig. 2) and in the male member (Fig. 3) the stem 13 and the plate 11, the stems in each case extending perpendicularly from a central portion of the plate. The stems are respectively formed with an annular beveled shoulder 14 (Fig. 4) and 14^a (Fig. 5), and a reduced neck 15 (Fig. 4) and 15^a (Fig. 5). This formation is then employed to complete the two members F and M.

In the case of the member F the reduced neck 15 is inserted through an aperture in the plate 16 and is turned upon itself as indicated at 16^a (Fig. 2) to rivet the plate 16 in place upon the neck 15 and against the shoulder 14. The plate 16 may have a depression around the central aperture as indicated in Fig. 2, so that upon completion

of the riveting operation a surface will be presented to receive the ornament 24 which will be free from upstanding projections that might cause fracture or injury to the ornament. The peripheral edge of the plate 10 is turned inwardly as shown at 10^a to fix the spring in position.

The spring 17 includes two legs 18 located on opposite sides of stem 12 and terminating in the resilient projectings 19, parts of which normally project inwardly through apertures 20 of stem 12 as shown in Figs. 1, 2, and 6.

In the case of the male member M, the neck 15^a is closed at its extremity and the closed end is inserted into the interior of a hollow knob 21 which forms an integral part of a member 22 which includes the peripheral flange 23. The member 22 is united to the stem 13 by providing pressure in a suitable manner to deform the neck 15^a within the knob 21 (see Fig. 3) so as to develop said neck 15^a in the nature of a ball α which completely engages the interior surface of the knob 21 and conforms to the interior form thereof. The result of this union is to provide a male member composed of two parts practically inseparable from each other and in which there is no possibility of relative motion and disconnection as between plate 11 and stem 13 such as sometimes occurred in some of the prior art structures.

In the section shown in Fig. 2, the stem 12 comprises an integral part of the member 10 which in this instance constitutes the head of the section, and the free end of the stem 12 is in riveted connection with the member 16, which in this instance comprises the base 40 of the section. As shown in Fig. 3, the stem 13 comprises an integral part of the member 11, which comprises the base of this section, and said stem is in riveted connection at its outer end with the member 22, which comprises the head of this section of the button. The section of the button shown in Fig. 2 comprises the female portion of the button and the interior dimension of the stem 12 is arranged to accommodate and receive the knob 21 of the section shown in Fig. 3, which comprises the male portion of the button. The proportion and arrangements of the parts are such that the locking projections 19 of the spring 17 enter the undercut annular groove b of the knob 21 as illustrated in Fig. 1, to detachably connect the male and female sections with each other. It will be observed that in both Fig. 2 and Fig. 3 the enlargement of the stem 60 represented by the turned-over edge 16^a of Fig. 2 and the ball 21 of Fig. 3 approximate and do not exceed the normal cross-section of the stems 12 and 13 respectively.

With the novel arrangement described and illustrated, each section of the button

comprises two parts riveted together in a single operation, thus reducing the parts as well as the operation of uniting the same to the simplest possible form. Furthermore, because of the fact that the deformed neck 15^a practically fills the interior of the knob 21 and conforms to the interior shape thereof, the knob becomes virtually a solidly seated ball of maximum strength. For this reason the metal of which the neck 15^a and the knob 21 is composed may be lighter than was necessary in existing forms of buttons, and yet will possess greater strength in the completed product. This feature of the new structure permits the elongation represented by 13 and 15^a to be effected by simple drawing operations. Notwithstanding that a drawing operation causes a progressive diminution in wall thickness, the structural organization of the combined elements is such that when the parts 13 and 15^a are formed by drawing, the ultimate product will nevertheless possess adequate rigidity and requisite strength.

The new structure also makes it possible to preserve or to readjust the condition of the spring 17 since it is visible and accessible as is indicated in Figs. 2 and 6. In addition to the above, the improved construction makes it possible to supply the sections of the button in completely assembled condition to the manufacturer of decorative buttons and makes it possible for this manufacturer to combine the decorative elements 24 with the button sections without requiring said manufacturer to participate in any way in the assembly of the elements of said button sections.

In addition to their other functions the annular shoulders 14 and 14^a constitute reinforcements which prevent collapse of the stems 12 and 13 under the pressure applied in the manufacture of the button members. Furthermore the axial passage which extends completely through the stem 12 permits acid used in the operation of finishing the button to pass through and out and to be thereby harmlessly disposed of.

Various changes in the specific forms shown and described may be made within the scope of the claims without departing from the spirit of my invention.

I claim:

1. A detachable cuff button section comprising a deep central stem having a portion near its free end reduced from the normal cross section of the stem to form a shoulder on the stem and then adjacent to said reduced portion an enlargement approximating and not materially exceeding the normal cross-section of the stem, two plate-like members, one of said plate-like members being adapted to lie against the outer surface of a cuff while the other plate-like member is adapted to be inserted loosely through the

buttonhole in a cuff and in said position to coact detachably with a complementary cuff button section, one of said plate-like members being an integral extension of the stem
5 while the other is non-integral, the non-integral plate-like member being provided with a central aperture smaller than the normal cross section of the stem and seated against the shoulder of the stem, said aperture cor-
10 responding closely to and having edge walls in contact with the reduced portion of the free end of the stem, the enlargement of the stem being in contact with a surface of the plate and at such distance from the shoulder
15 of the stem that the plate is firmly held and retained in place between the said shoulder and the said enlargement.

2. A detachable cuff button section comprising a deep hollow central stem having
20 a portion near its free end reduced from the normal cross-section of the stem to form shoulders on the stem, said reduction being outwardly bevel-wise in each direction above and below the narrowest part of said re-
25 duced portion of the stem, whereby said shoulders incline away from said narrowest part, an enlargement, adjacent to said re-
duced portion, approximating and not ma-
30 terially exceeding the normal cross-section
35 of the stem at the free end of the stem, two plate-like members, one of said plate-like members being adapted to lie against the outer surface of a cuff and being an integral extension of the stem, while the other plate-
40 like member is non-integral and is adapted to be inserted loosely through the button-
45 hole in a cuff and in said position to co-act detachably with a complementary cuff but-
50 ton section, the non-integral plate-like mem-
ber having an enlarged hollow knob and being provided with a central aperture of the same circumferential dimensions at its narrowest part as the exterior circumfer-
ential dimensions of the narrowest part of the reduced portion of the stem, said aperture being bounded by oppositely extending bevelled shoulder-engaging portions seated in close, tightly wedged contact with the bevelled shoulders of the free end of the stem adjacent to the narrowest part of its reduced portion.

In testimony whereof I have hereunto set
my hand.

JINDRICH WALDES.
